UNITED STATES PATENT OFFICE.

SALEM A. BAKER, OF INDIANAPOLIS, INDIANA, ASSIGNOR OF ONE-THIRD
TO JAMES A. STEWART, OF INDIANAPOLIS, INDIANA.

DOOR-HANGER.

No. 831,134.

Specification of Letters Patent.

Patented Sept. 18, 1906.

Application filed May 25, 1905. Serial No. 262,147.

To all whom it may concern:

Be it known that I, SALEM A. BAKER, of Indianapolis, county of Marion, and State of Indiana, have invented a certain new and useful Door-Hanger; and I do hereby declare that the following is a full, clear, and exact description thereof, reference being had to the accompanying drawings, in which like numerals refer to like parts.

10 The object of this invention is to provide improved means for supporting and handling car-doors. Herein the invention is shown in connection with the door of a stock-car, and in practice the invention would be used chiefly in that connection; but I do not wish it to be limited to stock-car doors.

One feature of the invention consists in inclining the upper hangers so that they cannot escape from the upper track, although if 20 the same hangers were spread they would escape from the track. With a hanger thus arranged it would be placed on the track or the track placed in the hanger by turning them at a right angle to each other; but when 25 they are not at a right angle to each other the hanger will not escape from the track.

The various features of the invention will be understood from the accompanying drawings and the following description and claims.

30 In the drawings, Figure 1 is a side elevation of a stock-car with the door closed, the ends of the car being broken away. Fig. 2 is a perspective view of the inner surface of one of the hangers in normal position on the upper track, a portion of the track being broken away and parts being shown in dotted lines. Fig. 3 is the same as the upper part of Fig. 2 with a part of the hanger broken away and showing the hanger in position while being 35 placed on the upper track. Fig. 4 is the same as the upper part of Fig. 2 with the lower part of the hanger broken away and the upper part of the hanger partially in vertical section. Fig. 5 is a vertical transverse section of the upper track and means for supporting the same, the hanger being shown partly in vertical section and partly in elevation. Fig. 6 is a perspective view of the outer end of the arm that carries the upper 45 track.

In detail, 10 represents the lower longitudinal beam of the stock-car; 11, one of the side casings of the door; 12, the upper longitudinal beam, and 13 the roof. To the upper

beam brackets 14 are secured for supporting 55 and holding the upper track 15. The brackets 14 have a horizontal groove 18 to receive the rib 19, extending centrally and longitudinally of the upper track 15 and along its back surface. The bolt 20 passes through 60 the upper track, the rib 18, and the bracket 14 for mounting them. The upper track is recessed at 21 longitudinally, so as to prevent the sliding door or hanger catching on the heads of the bolts 20. 65

The upper hangers 26 have each an arm that extends upwardly and is inclined from a vertical line. The inner surface of the upwardly-extending hanger is recessed to receive the upper track 15, or, in other words, 70 to permit the hanger to be placed on the track. The upper and lower surfaces of the recessed portion of the hanger are each adapted to engage the upper and lower edges of the upper track, as indicated in Figs. 3 and 4, 75 and each curved so as to diminish the bearing-surface between them and the track. The portion of those surfaces which engage the track when in proper position is sharply curved to reduce the bearing-surface to a 80 minimum. There is a flange or lip 28 on the inner face of the hanger that extends downwardly so as to overlap the upper track, and the hanger has a similar upwardly-extending flange or lip 29, that overlaps the lower edge 85 of said track, as appears in Fig. 2. These overlapping flanges or lips prevent the hanger from escaping from the track. They are curved so that when the upper arm of the hanger is vertical it may readily be placed on 90 and over the upper track, but when in an oblique position it cannot escape therefrom.

What I claim as my invention, and desire to secure by Letters Patent, is—

1. The combination with a car having an upper track for the door, and a door, of hangers secured thereto for supporting the door slidably upon said track, said hangers having flanges overlapping the upper and lower edges of said track, and being out of vertical 100 alinement with each other, the upper parts of said two hangers extending obliquely of the track in opposite directions with reference to each other.

2. The combination with a car having an upper track for the door, and a door, of hangers secured thereto for supporting the door slidably upon said track, said hangers having

flanges overlapping the upper and lower edges of said track, and being out of vertical alinement with each other, the upper and lower bearing-surfaces in said hangers being curved substantially as shown, and the upper parts of said two hangers extending obliquely of the track with reference to each other.

In witness whereof I have hereunto affixed my signature in the presence of the witnesses herein named.

SALEM A. BAKER.
